UNITED STATES PATENT OFFICE.

MARGUERETTE ELIZABETH PURDY, OF RIDGEFIELD PARK, NEW JERSEY.

DESIGN FOR A LADY'S HAT-FASTENER.

No. 39,589.

Specification for Design.

Patented Sept. 29, 1908.

Application filed June 24, 1908. Serial No. 440,199. Term of patent 7 years.

To all whom it may concern:

Be it known that I, MARGUERETTE E. PURDY, a citizen of the United States, residing at Ridgefield Park, in the county of Bergen and State of New Jersey, have invented a new, original, and ornamental Design for Ladies' Hat-Fasteners, of which the following is a specification, reference being had to the accompanying drawing, forming part thereof.

I claim:

The ornamental design for a ladies' hat fastener, as shown.

Witnesses:

HARRY G. PURDY,
A. H. BRADLEY.

MARGUERETTE ELIZABETH PURDY.
